UNITED STATES PATENT OFFICE.

THOMAS McFEELY, OF FOLCROFT, PENNSYLVANIA, AND LANDIS ROMICK, OF NILES, OHIO, ASSIGNEES TO THOMAS McFEELY COMPANY, A COPARTNERSHIP CONSISTING OF THOMAS McFEELY AND LENORE McFEELY, BOTH OF FOLCROFT, PENNSYLVANIA.

BRAN AND MIDDLING FINISHER.

1,141,969.

Specification of Letters Patent.

Patented June 8, 1915.

Application filed August 23, 1911. Serial No. 645,494.

To all whom it may concern:

Be it known that we, THOMAS McFEELY and LANDIS ROMICK, citizens of the United States, and residents of Folcroft, Delaware county, Pennsylvania, and Niles, Trumbull county, Ohio, respectively, have invented certain Improvements in Bran and Middlings Finishers, of which the following is a specification.

10 One object of our invention is to provide a machine which will successfully and efficiently remove glutinous middlings from bran or broken wheat without pressure or other destructive action on said particles; it being especially desired that the machine shall be of such design that practically all 15 of the valuable middlings shall be removed from the bran or other material under treatment.

20 We further desire to provide a machine for doing the work above noted with novel means for causing the disengagement of the particles of middlings and gluten from the bran, etc., to which they are attached.

25 These objects and other advantageous ends we secure as hereinafter set forth, reference being had to the accompanying drawings, in which:—

Figure 1, is a longitudinal vertical section 30 of a machine constructed according to our invention, and Figs. 2 and 3 are transverse vertical sections respectively on the lines *a—a*, and *b—b*, Fig. 1.

In the above drawings the machine is 35 shown as provided with base members 1 on which is mounted a frame consisting of two end members 2 and 3 connected by a pair of top members 4 and a pair of bottom members 5. Carried by the end members 2 and 3 40 of the frame are bearings 6 and 7 for a shaft 8 which may be driven from any suitable source of power.

Within and carried by the frame is a substantially cylindrical casing concentric with 45 the shaft 8 and formed in two semi-cylindrical parts 9 and 10 each provided with outwardly extending flanges along its longitudinal edges; there being bolts in said flanges for connecting together the said two sections.

50 It is to be particularly noted that the sections 9 and 10 are of different diameters and as shown in the drawings, the upper section has the larger diameter, so that there

are formed two horizontal ledges 11 along 55 the lines of its junction with the lower section and by reason of the difference in diameter of said sections the volume of the upper section is materially greater than that of the lower.

At the end of the machine adjacent the part 2 of the frame is a hopper 12 for the reception of the material to be treated, there being an opening 13 at the top of this hopper through which a discharge spout may be 60 connected, but shown in the present instance as closed by a cover 14. This hopper opens into one end of the main casing 9—10 and there is a discharge opening 15 at the opposite end of said casing provided with a 65 discharge spout 16 normally closed by a weighted valve 17.

Upon that portion of the shaft 8 extending into the hopper 12 are mounted two conveying blades 18, although it is obvious 70 that any other suitable number of blades may be used for the purpose of forcibly transferring the material from the hopper into the adjacent end of the casing. On the main portion of the shaft within the casing 75 are mounted a number of sets of radially projecting beater arms 19 and 20 each preferably having one face inclined so that it assists in conveying material from the hopper through the casing to the discharge end 80 thereof and at the same time so engages the material as to give this a rotary motion relative to the shaft.

We preferably so proportion the arms that those indicated at 19 for example, are 85 shorter than the arms 20 which project opposite them in the same line from the opposite side of the shaft, and in the present instance we have illustrated adjacent pairs of the arms 19 and 20 as spaced apart and 90 displaced 90° relatively to each other.

Formed integral with, or otherwise fixed to the cylindrical casing 10 are mounted a series of abutments 21, arranged in sets of two and each having a substantially plane 100 radial face. Each set of these abutments is spaced apart from the adjacent set to permit of the passage between them of one pair of the arms 19 and 20; it being noted that said abutments taper from the surface 105 of the casing section 10 on which they are mounted inwardly toward the shaft. With this arrangement of parts, the shaft 8, under

operating conditions, is driven at a suitable speed and the untreated bran is delivered to the hopper 12. By means of the blades 18 it is forced from said hopper into the 5 adjacent end of the cylindrical casing 9—10, where it is engaged by the various pairs of arms 19 and 20 and given a violent rotary motion. During the resulting rotation, however, the bran or other material under 10 treatment is violently brought into contact with the plane faces of the abutments 21 as well as with one of the ledges 11, with the result that the granules of gluten adhering to said bran are forcibly detached without 15 being in any way injured, as would be the case were they subjected to a crushing pressure.

It is especially to be noted that by our machine the material under treatment is at no 20 time crushed or ground, but is forcibly thrown against the plane faces of the abutments interposed in the path and provided by the abutments 21 and the ledge 11.

We have found that in order to secure the 25 best results, the velocity of rotation of the material under treatment should be alternately increased and decreased instead of being uniform as would be the case if such material were permitted to rotate or whirl 30 in the casing under the action of the arms alone and that by making the section 10 of greater diameter than the section 9, the violently rotating or whirling mass of material 35 changes its velocity as it passes from one section to the other and caused the machine to work at the highest efficiency.

Owing to the inclined face provided on 40 each of the beater arms, the material under treatment is gradually moved from the hopper end of the casing to the discharge end thereof and finally enters the spout 16, from which it is automatically discharged by the swinging outward of the valve 17 when the

pressure against it becomes sufficiently great. This material discharged consists of 45 a mechanical mixture of clean bran and granules of middling and gluten and it is thereafter subjected to any suitable process for separating these two substances. We have found by actual prolonged use of the 50 machine that it rapidly and most thoroughly separates the gluten and middlings granules from the bran without in any way injuring or reducing the commercial value of the said 55 gluten. It is to be noted that one of the ledges 11 likewise serves as an abutment having a plane radial face, and materially assists in freeing the glutenous granules from the bran.

We claim:—

The combination in a bran and middlings finisher of a casing consisting of semicylindrical top and bottom sections of which the bottom section is smaller in diameter than the top section and has laterally extended 60 flanges along its longitudinal edges forming plane ledges within the casing; a series of abutments extending inwardly from the inner surface of said casing; a rotary shaft 65 extending through the casing; with beater arms on the shaft placed to be operative between the abutments and formed to convey material through the casing.

In testimony whereof, we have signed our names to this specification, in the presence 70 of two subscribing witnesses.
